DEVICE TO STRAIGHTEN OUT RAW
TOBACCO LEAVES

Oswald Erich Eissmann, Richmond, Va., assignor
to "Universelle" Cigarettenmaschinenfabrik,
J. C. Muller & Co., Dresden, Germany

Application February 19, 1938, Serial No. 191,435

8 Claims. (Cl. 198—30)

This invention relates to a separator for tobacco leaves, more particularly to a device to straighten out raw tobacco leaves, which has for its object to provide means which will enable the tobacco leaves to be separated from each other so as to fall into different channels as they are conveyed by the traveling belt, and at the same time one of the objects is to arrange such tobacco leaves in alignment with the general direction of the travel of the belt.

For this purpose the invention consists of two traveling belts arranged spaced from each other, one preferably above the other at the end portions thereof, so that as the leaves fall off the first traveling belt they drop upon the adjacent end of the second traveling belt, and means disposed between said traveling belts for guiding the leaves so as to align them in the general direction of movement of the second traveling belt. These interposed means consist, in the embodiment shown, of inclined plates and also inclined edges, so that as the tobacco leaves drop from the first traveling member upon the inclined edges of the plates they are guided by such edges, first into an alignment position and, secondly, into a downward direction towards and upon said traveling apron. The leaves that drop upon the plates themselves gradually descend upon the inclined surface thereof until they reach the bottom of the plates and are directed thereby upon the traveling apron.

Thereby, by the means described, a separation junction in the path of the tobacco leaves has been provided, which, as before stated, efficiently separates the leaves and causes them to be dropped in the various channels along the traveling apron.

The invention will be more fully described hereinafter, the embodiments are shown in the drawing, and the invention will finally be pointed out in the claims.

In the accompanying drawing,

Figure 1 is a perspective view of the improved separator for raw tobacco leaves;

Figure 2 is a side view, partially in section, taken on line 2—2 of Figure 3, and seen in the direction of the arrow; and

Figure 3 is a vertical transverse section taken on line 3—3 of Figure 2.

Similar characters of reference indicate corresponding parts throughout the various views.

Referring to the drawing and more particularly to Figure 1, the traveling apron 10 moves over the roller 11 in the direction of the arrows 12 and 13. The apron 10 is inclined, the upper

portion traveling upwardly in order to carry and transport the tobacco leaves 15 dropped upon the upper surface of said apron 10. A housing 16 is provided with bearings 17 in which the shafts 18 of the roller 11 rotate. The housing 16 has parallel upstanding walls merging into inclined walls 19; the end of the housing is closed by an end wall 20 forming part of the housing. This housing has its top open, as also the end opposite the rear wall 20. Disposed below the roller 11 is another roller 21 having shafts 22 in bearings of the side walls 23 of a traveling apron frame, and between the two side walls 23 the apron 25 is disposed, which apron has its upper surface moving in the direction of arrow 26 and its lower portion 27 moving in the opposite direction.

The space between the two side walls 23 is in the neighborhood divided into three parts by means of two longitudinally extending partitions 28 and 29 which extend along the entire length of belt 25 and terminate at each end thereof. These partitions 28 and 29, as also the side walls 23, are each provided with strips having a triangular shape, with the base of the triangle below and the peak of the triangle extending upwardly. These strips 30, 31, 32, 33, 34 and 35 are suitably secured to the partitions 28 and 29 and the side walls 23 by gluing or other suitable fastening means. If desired the side walls of the hypotenuse of these triangular strips may be covered with leather or similar material having an extended portion adjacent to the upper surface of belt 25, so as to prevent any tobacco leaves from getting in between the lower surface of these strips and the belt 25.

It will have been noted that the upper end part of apron 10 is above the lower end part of apron 25, whereby the accumulated tobacco leaves 15, disposed crisscross one upon the other, may drop from the apron 10 upon the apron 25 and be guided in the channels formed by the partitions and side walls, and by such dropping down be guided by the inclined walls of the strips into such channels and dispose themselves in alignment with the general direction of the movement of apron 25, as indicated by arrow 26. However, not all of the tobacco leaves, which, as seen in Figure 1, are of an elongated form, take the desired position as just described, but this break in the aprons, causing what may be called a waterfall action, serves to bring about, together with the inclined walls of the strips, a general alignment of the tobacco leaves as they are forwarded by the apron 25.

A further improvement consists in providing between the end of apron 10 and the end of apron 25 disposed below, a plurality of plates 40 inclined, as shown in Figure 3. These plates are 5 triangular in shape, with the edge 41 abutting the end wall 20, the lower edge 42 of the plates abutting the top surface of the partitions 28 and 29, and the third edge of these plates 40 being inclined, as shown in Figure 1, extending from a 10 position close to the upper apron 10 to a part generally indicated by 44 on the partition 28, and the other plate, which is parallel thereto, extending to a similar position on the partition 29. Preferably, the walls 19 of the housing are parallel 15 with these plates 40, whereby the plates 40, whether two or more in number, are arranged parallel with each other and with the housing wall 19 and are all inclined. The walls 16 are parallel with each other. It will be noted from 20 Figure 3 that the upper apron 10 is disposed offset laterally with the lower apron 25, and that these walls 16 and 19 and plates 40 form three channels for guiding tobacco leaves from the upper apron 10 to the lower apron 25.

25 As shown in Figure 3, the uppermost edge of one wall 16 is about vertically above the partition 28. The uppermost edge of the first plate 40 is approximately above the partition 29, the uppermost edge of the second plate 40 is approximately above the side wall 23.

With the disposition of the parts as described and shown in Figures 1 and 2, the tobacco leaves fall off the apron 10 upon the edges 45 of the plates 40, and as these edges are inclined, as 30 shown, the leaves ride along the same, and due to the relative position of the leaves upon these edges during this descending action, that portion of the leaf which is heavier than the other portion will determine the future movement of that 35 leaf. Some leaves will align themselves longitudinally with the edge 45 and descend along the edge until the ends of the leaves are guided by the inclined walls of one of the strips 30, 31, 32, 33, 34 or 35; other leaves will ride along the 40 surface of the plate 40, while others will topple over from one compartment to another with the edges of the plates acting as pivots, but the general effect and the object of providing these plates is to cause the leaves to be shifted from the criss-cross fashion into which they are gathered on 45 apron 10 and deposited in isolated positions on apron 25, longitudinally aligned with the direction of movement of apron 25, as indicated by the arrow 26, in the channels formed between the 50 side walls 23 and the partitions 28 and 29.

In Figure 2 is shown a side view taken on line 2-2 of Figure 3, seen in the direction of the arrows, and the various arrows 47, 48, 49, 50, 51, 52 and 53 indicate the direction taken by the various 55 leaves in their descending action from the upper apron 10 to the lower apron 25, the arrow 54 indicating the return movement of the apron 25.

The inclined plates 40 may be disposed at an angle of about 30° to the horizontal, which, as 60 shown in Figure 3, has proven satisfactory. In the embodiment, plates 40 merge into guide walls 29 extending along the aprons. The ends of the aprons, as also the inclined guiding means described, are enclosed by a housing 16, the walls 65 of the housing 16 being preferably inclined so as to act in portions thereof in the same manner as the inclined plates 40.

From the foregoing description and embodiment shown in the drawing, it will have been 70 noted that the invention generally consists of a

feed apron terminating above the entrance end of another feed apron, the second feed apron being provided with longitudinal channels having inclined side walls, whereby the leaves, when descending from the first apron to the second 5 apron, are guided so as to partake of a longitudinal position in alignment with the direction of the movement of the second feed apron. The partitions which form the channels on the second feed apron are of general triangular form 10 with the peak of the triangle uppermost so as to provide inclined guide walls. Furthermore, the first or upper feed apron is laterally offset relative to the second apron and the space immediately below the discharge end of the first apron 15 is divided into compartments by inclined walls and, preferably, by triangular plates, so that as the leaves fall upon the edges of these plates or upon the plates themselves the leaves are caused to be aligned. As they approach the second or 20 lower apron they are then carried in an aligned position by the second apron in the direction of its movement.

By the structure disclosed, a superimposed 25 bundle of tobacco leaves in arbitrary positions is readily separated and caused to be moved forward by the second apron in isolated positions and in alignment with the direction of movement of the second apron.

This invention is especially adapted for the 30 handling of large quantities of tobacco used daily in the manufacture of tobacco for its further uses. The present tendency is to meet the demands of the customers who wish to have the completed product relatively as large as possible, 35 and this necessitates the placing of the tobacco leaves in a position so as to be introduced lengthwise into the tearing machine. Though it may be necessary to provide a larger tearing machine, it is not desirable to increase the accessories 40 thereto, and it is preferable to adhere to the narrow width of the feed apron heretofore used, and, if desirable, to place two aprons, or belts, side by side, or, if a double width belt is desired, 45 partitions can be installed therein.

The invention above described enables this feed belt, acting in conjunction with the tearing machine, to operate automatically without any attendance, since, in the invention described, 50 the tobacco arrives on a feed belt which is situated above, one and a half times the belt width higher than the actual feed belt, operating in conjunction with the tearing contrivance. The former or upper belt is displaced about 30° in relation to the lower feed belt, and the tobacco 55 drops over into compartments or chutes which are placed obliquely about 30° and which are inclined less than 45°, turning the tobacco leaves somewhat lengthwise and, furthermore, dividing them into various zones. The exact lengthwise 60 alignment of the leaves takes place when the leaves drop from the chute or chutes and touch the feed belt which acts in conjunction with the tearing contrivance. The high speed of the latter belt, that is, the lower belt, then turns the leaves lengthwise, so that they are conveyed to the tearing contrivance in a lengthwise position. It will, therefore, be seen that in connection with the structure described a leaf, 65 though placed in any position, lengthwise or crosswise, or otherwise, upon the upper apron, and though falling upon the inclined edges 45 in any position, as soon as an end of the leaf is brought in contact with the lower apron, the lower apron arranges it lengthwise.

In the embodiment there have been shown two inclined plates to operate as two inclined walls; also there have been shown two side walls along the apron 25 divided by two partitions into three channels. The number of compartments, chutes, plates, partitions and channels is not an essential feature of the invention, since more or less can be provided.

I have shown an embodiment of my invention, but I do not wish to be limited to the details thereof, as changes may be made therein without departing from the spirit of my invention as defined in the appended claims.

I claim as new:

- 15 1. In a separator for tobacco leaves, having a feed apron for transporting leaves in arbitrary positions in respect to each other and for discharging such leaves therefrom, a second apron having its receiving end disposed below the discharge end of the first apron, the combination of partitions having inclined walls disposed longitudinally of the second apron and forming a channel for guiding the descending tobacco leaves on the second apron, and plates between 20 the aprons having inclined edges terminating at the partitions of the second apron, said plates being inclined to the horizontal, said second apron being laterally offset from the first apron, said inclined plates extending rearwardly below the discharge end of the first apron, whereby the tobacco leaves, as they are conveyed forward by the second apron, are carried in an aligned position in the direction of the movement of the second apron.
- 30 2. In a separator for tobacco leaves, having a feed apron for transporting leaves in arbitrary positions in respect to each other and for discharging such leaves therefrom, a second apron having its receiving end disposed below the discharge end of the first apron, the combination of partitions having inclined walls disposed longitudinally of the second apron and forming a channel for guiding the descending tobacco leaves on the second apron, and plates between 35 the aprons having inclined edges terminating at the partitions of the second apron, said plates being inclined to the horizontal, said second apron being laterally offset from the first apron, the receiving end of the second apron being vertically inward of the discharge end of the first apron, whereby the tobacco leaves, as they are conveyed forward by the second apron, are carried in an aligned position in the direction of the movement of the second apron, the second apron being offset vertically from the first apron.
- 40 3. In a separator for tobacco leaves, having a feed apron for transporting leaves in arbitrary positions in respect to each other, and for discharging such leaves therefrom, and a second apron having its receiving end disposed below the discharge end of the first apron, of means disposed between the discharging end of the first apron and the receiving end of the second apron, 45 for disentangling the tobacco discharged from

the first apron, said means including an inclined wall disposed at an acute angle laterally to the second apron and having an edge portion disposed at an acute angle longitudinally to the second apron, whereby tobacco leaves dropping upon said means are balanced on the edge portion thereof, and descend upon the second apron at either side of said means depending upon which part of the leaf is heavier, said second apron then moving the said leaf in longitudinally aligned position away from said means.

5 4. A separator for tobacco leaves, comprising a feed apron for transporting leaves in arbitrary positions to each other and for discharging such leaves therefrom, a second apron having its receiving end disposed below the discharge end of the first apron and offset laterally from the first apron, and plates inclined to the vertical having their upper ends adjacent to the upper apron and having their lower ends adjacent to the second apron, said plates having inclined edges.

10 5. A separator for tobacco leaves, comprising a feed apron for transporting leaves in arbitrary positions to each other and for discharging such leaves therefrom, a second apron having its receiving end disposed below the discharge end of the first apron, and offset laterally from the first apron, partitions longitudinally of the second apron and forming channels, and triangular plates disposed between the aprons inclined to the vertical.

15 6. A separator for tobacco leaves, comprising a feed apron for transporting leaves in arbitrary positions to each other and for discharging such leaves therefrom, a second apron having its receiving end disposed below the discharge end of the first apron, and offset laterally from the first apron, partitions longitudinally of the second apron and forming channels, and a housing having inclined outer walls and inclined plates parallel with said outer walls, the plates having inclined edges extending from the upper apron to the lower apron.

20 7. A separator for tobacco leaves, comprising a feed apron for transporting leaves in arbitrary positions to each other and for discharging such leaves therefrom, a second apron having its receiving end disposed below the discharge end of the first apron, and offset laterally from the first apron, partitions longitudinally of the second apron and forming channels, inclined plates extending from said partitions to the first apron, and a housing having inclined walls parallel with the inclined plates, said plates being of a triangular shape with the hypotenuse inclined from the upper apron to the lower apron.

25 8. In combination, two aprons disposed one above the other, with the discharge end of the upper apron vertically above the receiving end of the lower apron, and one apron offset laterally from the other, and inclined chutes disposed between the aprons, for guiding tobacco from the discharge end of the upper apron to the lower apron.

OSWALD ERICH EISSMANN. 30
